J. H. Shedd.

Water Meter.

No 88,259.

Patented Mar 23, 1869.

J. HERBERT SHEDD, OF WALTHAM, MASSACHUSETTS.

Letters Patent No 88,259, dated March 23, 1869.

IMPROVEMENT IN LIQUID-METERS

The Schedule referred to in these Letters Patent and making part of the same.

To all whom it may concern:

Be it known that I, J. HERBERT SHEDD, of Waltham, in the county of Middlesex, in the State of Massachusetts, have invented a new and useful Improvement in Meters, which can also be applied to pumps and engines; and I do hereby declare that the following is a full, clear, and exact description of the construction and operation of the same, reference being had to the accompanying drawings, making a part of this specification, and to the letters of reference marked thereon.

The application of my invention, represented in the accompanying drawings, is to a modification of the improved rotary pump, for which a patent was granted to your petitioner and William Edson, on the 19th day of January, A. D. 1864.

In practically working the invention secured by said patent, I found the shock arising from stopping and starting the fans to be injurious; and a principal purpose of my invention is to accomplish the object gained by stopping the fans, and yet, at no time while the apparatus is working, to allow a fan to come to a complete stand-still.

The construction and arrangement of the apparatus thus represented are as follows:

Figure 1 is a perspective view of the exterior.

Figure 2 is a front elevation.

Figure 3 is a cross-section.

Figure 4 is a longitudinal section.

Figure 5 is an elevation of the gear-wheels.

Similar letters refer to similar parts.

A is a cylinder, or chamber, of any suitable material, forming the body of the meter, in which the fans revolve.

B is a movable head to the cylinder, to complete the chamber in which the fans revolve.

C is a cover enclosing the gear-wheels, and made fast to the body, A, with a water-tight joint, and forming a secondary chamber enclosing the gear. Fluid under pressure in the cylinder A, might, to a limited extent, escape around the several shafts and be lost, or cause annoyance; but with the secondary chamber made fast to the primary chamber, by a tight joint, a vessel is formed, having only one opening, beside the ports, and that of such a nature as to be easily made tight by a stuffing-box, thus preventing the final escape of any fluid.

D E F are, respectively, fans, or blades, which revolve within the cylinder A, each alternately acting as a plunger and then as a diaphragm, by reason of a varying velocity, and thus, when in motion, constantly emptying and filling the cylinder with the fluid allowed to pass through it.

G H I are, respectively, eccentric-gear wheels, one of which is attached to each fan, and giving to it the varying velocity required.

J K L are, respectively, eccentric-gear wheels, answering to and working with the gear-wheels G H I, and, being held in a fixed position in relation to each

other on their axis, they insure the proper relative positions of the fans at all times.

M is a shaft forming the axis of the gear-wheels J K L, and is the only part of the moving apparatus which passes through the shell of the water-tight vessel formed by the cylinder A and the cover C.

When used as a meter, the counting, or recording-gear is attached to this shaft; when used as a pump, the power is applied to it; when used as an engine, the machinery to be driven is attached to it.

N is a stuffing-box around the shaft M, to prevent the escape of fluid from this opening through the shell of the water-tight vessel.

O is the inlet for fluid, and is to be attached to the supply-pipe.

P is the outlet for fluid, and is to be attached to the service-pipe.

The operation of the apparatus thus represented is as follows:

A fluid being admitted, under pressure, through the inlet O, and having free escape through the outlet P, will act with equal pressure upon the fans D and F, but in their position as represented, the fan D acts, by the short line of its gear, into a long line of its corresponding gear, and thus exerts considerable power to turn the axis M, while the fan F acts, by a long line of its gear, into a short line of its corresponding gear, and thus exerts much less power to turn the axis M.

The gear-wheels on the axis M are firmly attached to each other and to the axis, and the fan exerting the greater pressure will move forward with the fluid-pressure, and carry with it the other fan against the pressure.

By calculation, I find, that in an apparatus on the scale represented in the drawings, the fan D will move forward with a surplus power of one and seventy-eight hundredths ($1\frac{78}{100}$) pounds for every foot head of water brought upon it, after furnishing sufficient power to carry the fan F against the pressure. The motion of the fan D will also be much more rapid than that of the fan F, and will tend to overtake it on the outlet-side of the cylinder, thus forcing out fluid on that side, while the distance between the fans is increased on the inlet-side of the cylinder, thus tending to form a vacuum, which will be filled by fluid flowing through the inlet-pipe.

I have referred to the fan F, in this description, as a diaphragm; but in the position represented in the drawings it will soon cease to act as such, and be idle for a time, though still in motion, while its place is supplied by the fan E.

As the fans continue to revolve, F becomes a plunger, with a rapid motion, while D, running gradually slower, and idle for a time, though still in motion, finally takes its turn as a diaphragm, and then again more rapidly, to be a plunger.

Thus the fans, acting together, and constantly in motion, empty and fill the cylinder continuously; a given quantity of fluid is discharged at each revolution.

of a fan; and from a record of the number of revolutions, the amount discharged in any given time can be ascertained.

I do not herein allege the invention of any device claimed in the patent for a meter, of even date herewith, to S. P. Ruggles; but

I claim—

1. The fans D E F, within a cylinder, so arranged that one of them shall operate as a plunger, another moving tardily as a diaphragm, and the third being measurably ineffective in its transition from the condition of a diaphragm to that of a plunger, or from the condition of a plunger to that of a diaphragm, all operated by means substantially as described.

2. The combination of eccentric-gearing, as described, with a system of fans of varying movement, upon a common centre, in the manner and for the purpose herein shown.

3. The arrangement of the fan-chamber and the gearing-chamber, containing the parts hereinbefore recited, within a case, A, and cap C, whereby the whole shall be protected, with the occurrence of but one single joint, all as and for the purpose shown.

J. HERBERT SHEDD.
